HORIZONTAL-DISK PULVERIZER

Julius Niethamer, Whitestone, N. Y.

Application February 28, 1946, Serial No. 650,890

1 Claim. (Cl. 241—257)

1

This invention relates to pulverizers and, more particularly, to a rotary disk pulverizer having a grinding and shearing action on the material worked upon.

The primary object of the invention is to provide a pulverizer of the type which includes a disk rotatable about a vertical axis and having an upwardly disposed working face cooperating with the downwardly disposed working face on a stator disposed thereabove. Working faces on the rotor and stator are intended to be formed with sets of teeth which pulverize first by a rough shearing action to break up the material being worked upon, then by finer shearing action to cut the material into substantially uniform particles, and finally by grinding the material. It is further intended to perform the successive steps of pulverization in separate zones progressing radially outward from near, but not at, the centers of the rotor and stator to the peripheries thereof, and to dispose the teeth on the working faces of the rotor and stator at such angles as to exert on the material a positive outward force as well as a centrifugal force so as to feed the material through the successive working zones.

Still another object is to provide a simple and a unique arrangement for varying the spacing between the rotor and stator of a pulverizer. More specifically, it is proposed herein to support a stator on a bearing ring, the ring being, in turn, supported at angularly spaced points on ears on the pulverizer housing. A plurality of angularly spaced bearing points or feet of varying depth are to be provided on the bearing ring so that the height of the rotor above the stator will depend upon the depth of the particular set of bearing points selected for seating on the housing bearing points. The effect of this arrangement is selectively to provide coarse, medium, or fine grinding merely by rotating the stator bearing ring so as to bring the desired set of bearing points into play.

Yet another object is to provide a variable feed control for governing the flow of material from a hopper to the working zones. More definitely, it is intended to provide a cone-shaped element supported above the stator by a boss-like bearing element which extends through the center of the stator, the cone bearing being affixed on the upper end of the motor shaft which drives the rotor so that the cone and its bearing rotate with the rotor. The cone lies within a throat at the bottom of a feed hopper, cones of varying effective height above the cone bearing being provided for varying the throat restriction.

Among the other objects is the provision of a turbine rotor removably secured to the periphery of the shearing and grinding rotor for feeding the pulverized material discharged from the

2

inter-rotor grinding zone to a discharge chute. In this connection it is intended to provide turbine blades substantially L-shaped and nesting with their inner angles complimentary with the lower, outer angle of the rotor, the legs of the L-shaped turbine blades being sufficiently high as to overlap a portion of the stator periphery. It is also intended to provide a ring for supporting the turbine blades on the rotor, the ring being so formed as to constitute a seal for preventing material from lodging beneath the rotor.

In addition, it is intended to provide a pulverizer which may be easily disassembled and assembled for cleaning. These and other objects will be apparent from the following specification and drawings, in which:

Fig. 1 is an elevation, partially in vertical section of the assembly;

Fig. 2 is an exploded view showing the inner parts in vertical section;

Fig. 3 is a plan view of the stator in inverted position;

Fig. 4 is a plan view of the rotor;

Fig. 5 is a plan view of the adjustment ring;

Figs. 6 and 7 are detailed sections along lines 6—6 and 7—7, respectively, of Fig. 5, and;

Figs. 8 and 9 are elevations illustrating alternate cones.

Referring now to the drawings, in which like reference numerals denote the same or similar elements, the machine as a whole is shown in Fig. 1 wherein there is shown a flat base 2 having legs 4 projecting upwardly to support the casing 6 of an electric motor controlled by an off-on switch 8 connected to a suitable source of electricity, not shown. The flat top of motor casing 6 supports the base 10 of a housing 12 secured on by bolts in recesses 14.

Housing 12 includes an upstanding, hollow cylindrical portion 16, the base of which accommodates the drive shaft 18 of the motor enclosed in casing 6. Ball bearings 20 rotatably support shaft 18 near the lower end of housing 12 and a grease cup 22 and passage therefrom is provided in the wall of cylindrical portion 22 for bearing lubrication.

A tubular rotor drive shaft 24 closely engaged over motor drive shaft 18 and held in non-rotating engagement thereon by a set screw 26 extends upwardly into an enlarged cylindrical portion of housing 12, the upper end of the rotor drive shaft being provided with annular, inwardly flanged shoulders 28 and 30 and terminating in a rectangular boss 32, as best seen in Fig. 2 for supporting and non-rotatably fitting with a rotor 34 complimentarily formed with a rectangular central opening 36 which non-rotatably fits on rectangular boss 32, and an annular recess 38 in its bottom arranged to nest with shoulders 28 and 30.

A shallow annular recess 40

surrounding central opening 36 is formed in the top wall of disk 34 for receiving the depending rim 42 of an outwardly flanged skirt 44 on a combined lock screw and feed control support 46, the screw portion 48 of which threads downwardly into an inwardly threaded axial bore 50 in the top of rotor drive 24.

Of particular importance is the arrangement of and form of teeth on the upper, working face of the substantially flat, disk-shaped body 52 of rotor 34, these teeth being as seen best in Figs. 2 and 4, and consisting of two sets integral- 10 ly formed with disk body 52 both of which sets are skewed so that their inner ends lie counter-clockwise of radii respectively intersecting their outer ends, as seen in plan view. The teeth 54 comprising the larger set terminate at their highest, inner ends 56 flush with the edge of recess 40 and have straight top edges 58 sloping downwardly towards their outer ends so, in effect, 15 as to merge with the upper face of the body 52 of disk 34 at the point designated 60. It should be further noted that a circumferential portion 62 of the upper face of disk 34 is beveled from point 60 to its outer periphery, the bevel of portion 62 being at the same angle of slope as the top edges 58 of teeth 54 so as to form a continuation thereof. Actually, teeth 54 continue from point 60 almost to the outer periphery of body 52, being there defined by slots 64 in the upper face of body 52. Slots 64 are angularly spaced from one another so as to define small teeth 66 therebetween, these small teeth being skewed somewhat more than the larger ones 54. The depth of slots 64 is such that their bottoms intersect at point 67 with the plane of beveled portion 62 so that, at point 67, all teeth 54 and 66 dwindle away, thus leaving a smooth grinding surface 68 immediately adjacent the outer periphery of disk 34.

The underside of rotor 34 is tapped at several points for threadedly receiving bolts 72 which hold on the Z-sectioned ring 74 of turbine 76, the L-shaped blades 78 of which are welded or otherwise rigidly secured to ring 76 with their surfaces radially disposed. Turbine blades 78 each comprise a foot 79 which underlies the lower edge portion of rotor 34 and a leg 80 which extends higher than the upper peripheral edge of the rotor so as to overlap the gap between the rotor and stator described below, the turbine running in an annular recess 82 in the body of housing 12. An outlet chute 86 extending from housing body communicates with turbine recess 82 and, preferably, an outlet tube 88 is connected on outlet chute for removing the ground material.

A stator 90 affixed above rotor 34 is formed with an annular central opening 92 surrounding the central boss 152 of lock screw and feed control support 46 so as to allow rotation of the latter therein. While stator 90 is preferably formed of one integral piece, it may be considered as comprising an inner ring 94, an outer ring 96, and cut-away portions 98 leaving spoke-like large teeth 100 therebetween. All of the teeth of stator 90 are skewed in the manner of those on rotor 34 but, in the case of stator 90 the inner ends of the teeth lie clockwise of radii intersecting their outer ends, as seen in plan. In Fig. 3 the stator is shown inverted. Otherwise, stator 90 is somewhat complimentary with rotor 34 in that large teeth 100 are narrowest, from top to bottom, at their inner ends 102 and have lower edges 103 inclined outwardly and down-

wardly, these edges preferably being beveled so as to present a knife-like edge.

The outer ring portion 96 of stator 90 has its lower face beveled as indicated at 104 so that the portions at the outer ends of the spoke-like large teeth 100 form a continuation thereof, and spaced slots 106, which are wedge-shaped in cross-section, define small teeth 108. In detail, slots 106 are deepest at their inner ends 109 so that the effective height of small teeth 108 is there greatest whereas the slots terminate at 110 so as to leave a substantially smooth grinding surface 111 adjacent the periphery of stator 90 to mate with the corresponding surface 68 on rotor 34.

Stator 90 is provided with four holes 112 for attachment by four screws 126 to an adjustment ring 114. Adjustment ring 114 is generally T-shaped in cross-section and comprises a depending ring portion 116 rotatably fitting in the cylindrical side wall 118 of housing 12, and an inwardly extending flange 122 drilled and countersunk at 124 for the screws 126 which affix it to stator 90. An outwardly extending flange 125 on adjustment ring has its periphery notched. In Fig. 5 it will be observed that there are three spaced sets of notches 128A, 128B, and 128C, these sets being selectively engageable over three pairs of ears 130 extending outwardly from housing 12, each pair being 120 degrees from the next. While the lower surface of ring 114 is flat at the outer corners of notches 128A, as illustrated in Figs. 2, 6, and 7 depending feet 132B and 132C extend downwardly from adjacent the outer corners of notches 128B and 128C, respectively, so that when ring 114 is rotated to bring the three notches 128A in registry with the three pairs of ears 130, ring 114 supports stator 90 above the position which it would occupy were notches 128A registered 20 with ears 130 and, of course, below the position which it would occupy were notches 128C so registered.

A hopper 134 having at its lower end a reduced throat 136 and an outwardly flanged flat base 138 also having nine notches 140 at its outer edge spaced to register with notches 128A, 128B, and 128C fits flatwise over adjustment ring 114, the ring 114 and hopper base 138 being held in position by three bolts 148 pivoted at 150 to housing 12 so that they may be swung up between ears 130 and into slots 128A, 128B, or 128C, depending upon the position selected for adjustment ring 114, and also into slots 140, there being wing nuts 146 on bolts 148 for holding the top assembly down. If desired, the inner flange 122 of adjustment ring 114 and the flat base 138 of hopper 134 may be suitably drilled, as at 148, for drift pins 150.

The combined lock screw and feed control support 46 is formed with an annular central boss 152 which rotates within annular central opening 92 of stator 90, as denoted above. The top wall of boss 152, which lies just higher than the upper surface of rotor inner disk 94, is formed as an inwardly flanged shoulder 154 and projecting upwardly from the shoulder is an axial post 156 on which fits a feed control cone 158A, 158B, or 158C. Each of the cones is provided with a flat base 160 which rests on shoulder 154, and axial bore 162 extending upwardly from the base for fitting over post 156. A pin 164 is press fitted in a suitable opening through the side wall of each cone, the inner end of the pin engaging in an L-shaped bayonet slot 165 which has a vertical portion and a foot portion extending clockwise

therefrom so that a cone may be fitted down on post 156, given a slight turn, and locked in place. On the side of each cone, a stiff wire 158 is soldered so as to lend a slight stirring motion to material fed therewith, the upper end of the wire 5 extending above the cone apex and terminating in a tip 170.

Figs. 8 and 9 illustrate alternate cones 158B and 158C respectively provided with cylindrical bases 160B and 160C for supporting the cones at various 10 levels above shoulder 154, thereby varying the restriction of hopper throat 136.

In operation, wing nuts 146 are loosened so as to allow bolts 148 to be pivoted out from the position shown in Fig. 1 so that hopper 134 can be 15 removed for installing the selected feed control cone 158A, 158B, or 158C. The cone selection will be based upon the coarseness of the material to be pulverized and the desired rate of feed from the hopper to the shearing and grinding zones. 20 Then, either before or after the hopper is replaced, adjustment ring 114 is rotated to bring the desired set of slots 128A, 128B, or 128C in registry with ears 130 so as to provide the desired spacing between stator 90 and rotor 34. By adjustment of 25 ring 114, a coarse, medium, or fine pulverization can be obtained. Then, with hopper 134 in place, bolts 148 are returned to their Fig. 1 position, wing nuts 146 are tightened, cover 170 is removed, the material to be pulverized is placed in hopper 30 134, and switch 8 is closed to start motor 6. Assuming that a fine pulverization and a fast feed is desired, the raw material will drop through hopper throat 136, the rotation of the cone 158A skewing to stimulate material flow therewith. 35 From throat 136, the material passes down through the spoke-like teeth 100 of stator 90, immediately after which it is sheared by the 40 operating large teeth 54 and 100 on the rotor and stator. As rotor 34 turns, counter-clockwise as seen in plan, the angularly skewed disposition of 45 its teeth is such that the inner ends lead the outer, thereby forcing the material outwardly as it is roughly sheared. The effect of the angular disposition of stator teeth 100 is likewise such that material forced thereagainst by the rotor will be wedged outwardly. These driving actions, together with centrifugal force, feed the roughly sheared material to the zone between small rotor teeth 66 and small stator teeth 108 (at which 50 points large teeth 54 and 100 have become small) where the roughly sheared material is sheared into small particles. As these small particles are fed outwardly, they are ground between smooth surfaces 68 and 111. When the particles have 55 been ground sufficiently to pass out between the adjacent peripheries of the rotor and stator, they are then engaged by the blades 78 of turbine 16 and impelled to outlet chute 86.

In addition to its functions in grinding per se, 60

the design of the rotor and turbine is such as to eliminate heat, as is particularly desirable in dry grinding. However, the device is also adapted for use as a colloid mill in that the lock screw 46, rotor 34, and turbine ring 74 substantially prevent passage of material, be it wet or dry, to the space beneath rotor 34 or into cylindrical portion 16 of housing 10.

I claim:

A pulverizer, comprising a housing enclosing a chamber having a side wall, an end member movable with respect to said side wall, a rotor rotatably mounted in said chamber, a stator rigid with said end member and adapted and arranged for spaced cooperation with said rotor, a set of ear pairs projecting from said casing, the ear pairs forming said set being angularly spaced with respect to one another, said end element having a plurality of sets of slots in the edge thereof each set of slots being arranged for registry respectively, with the spaces between the ears forming each pair with the material of said end member adjacent said slots engaged with said ears, the material adjacent one set of slots being of greater effective extent towards said ears than the material adjacent the others, whereby the spacing between the rotor and stator may be varied by adjustably moving said end element to bring the selected set of slots in registry with said spaces between the ears, bolts pivoted to said casing and adapted to swing between the ears forming each pair and into the selected slots, and nuts on said bolts for securing said end member in selected position.

JULIUS NIETHAMER.
